UNITED STATES PATENT OFFICE.

PHILO B. SHELDON, OF ERIE, PENNSYLVANIA, ASSIGNOR TO THE PHILO BURT MANUFACTURING COMPANY, OF JAMESTOWN, NEW YORK.

DESIGN FOR AN ABDOMINAL BANDAGE.

SPECIFICATION forming part of Design No. 35,226, dated October 22, 1901.

Application filed August 28, 1901. Serial No. 73,826. Term of patent 14 years.

To all whom it may concern:

Be it known that I, PHILO B. SHELDON, a citizen of the United States, and a resident of Erie, in the county of Erie and State of Pennsylvania, have invented and produced a new and original Design for an Abdominal Bandage, of which the following is a specification, reference being had to the accompanying drawing, forming a part hereof, which represents a perspective view of the invention.

The design presents at the back a number of vertically-extending strips *a* of equal length and running out of parallelism. From the upper parts of these strips projects a waistband *b*, and below this band at the front appears a stomach-pad *c*, joined to the strips *a*.

by two pair of straps *d*, the lower pair of which are fastened to the strips *a* at their lower ends and the upper pair of which are fastened to the strips *a* near their upper ends.

Having described my invention, what I claim as new, and desire to secure by Letters Patent, is—

The design for an abdominal bandage, as herein shown and described.

In testimony whereof I have signed my name to this specification in the presence of two subscribing witnesses.

PHILO B. SHELDON.

Witnesses:

J. M. SHERWIN,
L. H. COUSE.
